ICE CREEPER

Clarence Harvey, Canastota, N. Y.

Application November 20, 1942, Serial No. 466,319

5 Claims. (CL 36—61)

This invention relates to ice creepers designed as a permanent part of an overshoe, boot or the like.

The primary object of the invention is to provide an ice creeper which may be moved to a position within the space at the instep portion of a rubber or boot, where it will be out of the way when it is not desirable to use the creeper.

Another object of the invention is to provide an ice creeper which may be readily moved from its inactive position, to its active position, or to a point in contact with the heel of the overshoe on which the device is positioned, means being provided for exerting pressure on the ice creeper to hold it in place.

Still another object of the invention is to provide an ice creeper which will be exceptionally cheap to manufacture, and one which may be manufactured and mounted on overshoes, boots or the like, without the necessity of making extensive alterations in the overshoe or boot construction.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

Referring to the drawing

Figure 1 is a side elevational view of an overshoe equipped with an ice creeper constructed in accordance with the invention.

Figure 2 is a plan view of the creeper.

Figure 3 is a side elevational view of the ice creeper, showing the same as in its inactive position, within the instep of an overshoe.

Figure 4 is a sectional view illustrating a modified form of attaching means.

Referring to the drawing in detail, the body portion of the ice creeper is indicated generally by the reference character 5 and comprises a substantially wide length of sheet metal material, formed with an elongated opening 6, extending from a point adjacent to the forward end of the body portion, to a point substantially centrally of the body portion.

This elongated opening is designed to receive the button 7, which may be formed integral with the sole of the overshoe which is usually constructed of rubber.

As shown, the body portion 5 extends downwardly from the button 7, where it extends horizontally to lie flush against the outer surface

of the heel of the rubber, as shown by Fig. 1 of the drawing.

Portions of the body portion 5, adjacent to the side edges thereof, are extended upwardly as at 8, providing stops to engage the vertical front wall of the heel of the rubber, to hold the body portion 5 against rearward movement on the heel of the overshoe, beyond a certain point.

The reference character 9 designates a rubber band which has its ends vulcanized to the overshoe, at points adjacent to the instep portion of the overshoe, the intermediate portion of the rubber band being spaced from the instep of the overshoe, providing a rest for the body portion. It is obvious that when the body portion is moved from its active position as shown by Fig. 1, to the inactive position as shown by Fig. 3, the resiliency of the rubber band 9 will act to hold the body portion into close engagement with the bottom of the rubber, the spurs 8 embedding themselves slightly in the rubber, to further insure against the body portion slipping.

When it is desired to move the body portion to its active position, the body portion is pulled rearwardly until the spurs contact with the vertical wall at the front of the heel of the overshoe. The elastic band 9 now exerts an upward pull on the body portion to hold it into close engagement with the heel of the overshoe.

Spurs indicated at 10 are stamped from the body portion 5 adjacent to the rear end thereof, and are adapted to embed themselves in the snow or ice surface over which the person using the device is walking.

In the form of the invention shown by Fig. 4, the button, which is indicated by the reference character 15, is of the type which may be riveted to the overshoe, at a point within the instep thereof. This type of button affords means whereby the ordinary overshoe may be supplied with an ice creeper, constructed in accordance with the invention.

The reference character 16 designates the body portion of the ice creeper, which is formed with an elongated opening to receive the button.

From the foregoing it is believed that the operation of the ice creeper will be apparent, and that further detailed disclosure of the device and use, is unnecessary.

What is claimed is:

- An ice creeper embodying a wide body portion having an elongated opening adapted to accommodate a button of an overshoe, the button being secured adjacent to the instep portion of

the overshoe, an elastic band secured to the overshoe and adapted to pass over the body portion normally urging the body portion towards the sole of the overshoe, spurs forming a part of the body portion and adapted to bite into the surface over which the person using the overshoe is walking, and spurs carried by the body portion and adapted to engage the vertical front wall of the heel of the overshoe, on which the device is secured.

2. The combination with an overshoe having a button extending from the instep portion of the sole of a shoe, of an ice creeper embodying a wide plate having an elongated opening adapted to accommodate the button, slidably mounting the plate on the overshoe, and spurs extending upwardly from the body portion and adapted to rest against the front wall of the heel of the overshoe on which the device is positioned, surface-engaging spurs extending from the plate, and an elastic band secured to the overshoe and adapted to engage the plate, normally holding the plate into engagement with the overshoe.

3. The combination with an overshoe having a button extending from the instep portion of the sole thereof, of an ice creeper comprising a body portion having an elongated opening extending longitudinally thereof, said elongated opening adapted to accommodate the button, slidably mounting the body portion on the overshoe, means for restricting movement of the body portion towards the heel of the overshoe, surface-engaging spurs extending from the body portion, and yieldable means secured to the overshoe and

engaging the body portion for holding the body portion into close engagement with the overshoe.

4. The combination with an overshoe having a button extending from the instep portion thereof, of an ice creeper comprising a body portion having a longitudinally extended elongated opening formed intermediate the side edges thereof, said opening adapted to accommodate the button, slidably mounting the body portion on the overshoe, yieldable means carried by the overshoe and engaging the body portion, said yieldable means embodying a band adapted to normally urge the body portion into close engagement with the shoe, means for restricting movement of the body portion longitudinally of the sole of the overshoe, and surface-engaging spurs stamped from the body portion.
5. The combination with an overshoe having a button extending from the instep portion of the sole of the overshoe, of an ice creeper comprising a body portion having a longitudinally extending elongated opening formed therein, said opening adapted to accommodate the button, slidably connecting the body portion to the overshoe, means for restricting movement of the body portion longitudinally of the overshoe, yieldable means carried by the overshoe and adapted to overlie the body portion, normally urging the body portion into close engagement with the shoe, and surface-engaging spurs extending from the body portion.

CLARENCE HARVEY.
